UNITED STATES PATENT OFFICE.

GEORGE HERBERT WILLANS, OF GLOUCESTER, ENGLAND.

COMBINED FEED-WATER HEATER AND STEAM-SUPERHEATER FOR LOCOMOTIVE AND OTHER SMOKE OR FIRE TUBE BOILERS.

1,353,200.

Specification of Letters Patent. Patented Sept. 21, 1920.

Application filed October 15, 1918. Serial No. 258,274.

To all whom it may concern:

Be it known that I, GEORGE HERBERT WILLANS, a subject of the King of Great Britain and Ireland, residing at Gloucester, England, whose post-office address is 19 Alexandra Road, Gloucester, England, have invented certain new and useful Improvements in Combined Feed-Water Heaters and Steam-Superheaters for Locomotive and other Smoke or Fire Tube Boilers; and I do hereby declare the following to be a full, clear, and exact description of the invention, such as will enable others skilled in the art to which it appertains to make and use 15 the same.

This invention consists in a combined superheater and feed-water heater for locomotive and other smoke or fire tube boilers.

Superheater elements or steam superheating pipes have heretofore been inserted in the smoke tubes of locomotive, marine and similar types of boilers. It has also been heretofore proposed to insert feed-water heating pipes or elements in smoke or fire tubes of boilers. Further it has been proposed to insert feed-water heating pipes or elements in smoke or fire tubes of the usual group of such tubes containing steam superheater elements, but in this case the steam 25 superheater elements were omitted from the smoke or fire tubes containing the feed-water heating element or elements.

According to the present invention a steam superheating element and a feed-water heating element are inserted in one and the same smoke or fire tube of the boiler so that the fire gases flowing through said tube serve both for superheating the steam in the superheater element and for heating 35 the boiler feed-water in the feed-water heating element. Preferably the smoke or fire tube or tubes, each containing a superheater element and feed-water heater element, are smoke tubes of the usual group of such tubes 40 containing the set of superheater elements comprised in the superheater installation. Further the superheater elements in the smoke tubes, in which the feed-water elements are also inserted, are preferably of the well known short return-loop type, but such elements are, according to this invention, modified or so formed as to enable the feed-water heating element or elements, preferably of the U-pipe type, to be inserted in the smoke tube or tubes containing 45

the superheater element or elements. Further the superheater element is so formed or arranged within the smoke tube that it serves to more effectively break up the fire gases passing through the smoke tube and produce a better distribution of the gases over the heating surfaces of the feed-water heating and steam superheating elements, thus increasing the efficiency of the apparatus, and also tends to extend the life of the feed-water heating element or elements. 50

Further the construction and arrangements according to this invention are such that either of the feed-water heating elements in two adjacent smoke or fire tubes can be independently withdrawn from the respective fire tube without withdrawing the other element and without interfering with the superheater elements in the said smoke tubes. 55

The short return-loops of the superheater element, situated at or forming part of the element adjacent the fire box end of the smoke tube and extending forwardly toward the smoke box to about midway of the length of the smoke tube (or to a lesser distance as may be found suitable) are so formed or arranged that these short loops lie in parallel oblique planes in the smoke tube and adjacent the sides thereof, the return bend connecting the longitudinal pipes of the short return loops at the smoke box end of the short return loop portion of the element preferably lying in the central vertical plane (this return bend might however lie in a plane oblique to the central vertical plane) of the smoke tube, and the longitudinal saturated steam inlet and superheated steam outlet pipes of the element are bent laterally or outwardly so that these pipes lie adjacent the sides of the smoke tube and preferably in the horizontal central plane of the tube. The feed-water heating pipe or element, preferably of the U-loop type, is arranged between the aforesaid longitudinal steam inlet and outlet pipes of the superheater element and preferably in the vertical central plane of the smoke tube, the inner or return bend of the feed-water heating element within the smoke tube lying adjacent the short return loop portion of the superheating element. Preferably the feed-water heater comprises at least two U-loop pipes or elements one of which has its inlet end suitably connected to a pipe which receives 60

water from the tender or source of supply and its outlet end being connected with the water inlet end of the feed-water heater element in the adjacent smoke tube the outlet 5 end of this latter element being suitably connected to a pipe leading into the boiler the arrangement being such that the feed-water supplied to and passing through the first 10 element in direct communication with the supply passes from the said element into and through the feed-water heating element in the adjacent smoke tube and thence into the boiler.

The invention further consists in the several parts arranged in combination substantially as hereinbefore described with reference to and shown in the accompanying drawings in which,—

Figure 1 is a side view, partially in section, of a boiler smoke-box and the front end portion of a feed-water heater and superheater, constructed according to this invention. Fig. 1^a is a similar side view showing in section the rear end portion of 20 the said feed-water heater and superheater, for which there was not sufficient room at the right hand of Fig. 1, on the same sheet of drawings as Fig. 1.

Fig. 2 is a cross section, on the line A—A Fig. 1^a, through one of the boiler smoke tubes drawn to a larger scale.

Fig. 3 is a similar view to Fig. 2 but taken on the line B—B Fig. 1^a.

Fig. 4 is a front elevation, partly in section, looking in the direction of the arrow X Fig. 1, showing one half of the smoke box tube plate.

Like reference numbers indicate corresponding parts in the several figures of the 40 drawings.

In the drawings 1 indicates the barrel of the boiler, 2 the smoke box, 3 the smoke box tube plate and 4 the usual enlarged smoke tubes of the boiler into which the superheater elements extend. 5 are the usual relatively small smoke tubes of the boiler.

6 are the feed-water heater elements there being, in the example shown, three of these elements one extending into each of the 50 boiler smoke tubes 4 containing a superheater element of the short return loop type as hereinbefore mentioned. In the example shown the saturated steam inlet and superheated steam outlet ends, marked respectively 7 and 7^a, of the several superheater elements are bent upwardly and secured, in the usual or any suitable manner, to the bottom of the header 8 (of known or suitable form, in the smoke box 2. As clearly shown 60 in Figs. 2, 3 and 4, the longitudinal steam inflow and outflow pipes (forming continuations of the end portions 7, 7^a) of the superheater element extending into a smoke tube 4 are, for a portion of their length, 65 slightly greater than the total length of the

feed-water heater element 6 within the smoke tube, bent or set outwardly so that these pipes are a relatively wide distance apart and lie near the sides of the smoke tube 4. These pipes are marked 7^b, 7^c in 70 Figs. 1, 2 and 4. The pipes of the feed-water heater element 6 are situated one above the other so that this element lies in the central vertical plane of the smoke tube 4 and between the pipes 7^b and 7^c of the 75 superheater element.

As shown in Figs. 1^a and 3 the pipes, marked 7^d and 7^e of the short return loop portion of the superheater element are so formed or arranged that they, and their return bends or torpedo ends marked 8^b Fig. 1 lie in parallel oblique planes in the smoke tube 4 as hereinbefore mentioned, and the return bend 8^c at the opposite end lies in the central vertical plane of the smoke tube. 80

As clearly shown in Fig. 1 the legs or pipes of the U-shaped feed-water heater elements extend well forward into the smoke box so that the extremities of these pipes are well clear of the ends of the superheater elements in the smoke box, and the said extremities of the feed-water heater pipes are fitted with removable screw plugs 9 which when removed give access to the interior of the feed-water heater pipes for cleaning 95 purposes in a known manner.

The feed-water heater elements in adjacent smoke tubes are connected to each other by flanges 10 on short tubular pieces 11 on the adjacent pipes communication being 100 thus formed between the elements in adjacent smoke tubes. Similarly tubular connections 12 and 12^a with flanges 13 and 13^a respectively are connected to the inlet leg or pipe of the feed-water heating element 6 in 105 the lowermost smoke tube 4 (Figs. 1 and 4) and to the outlet leg or pipe of the element 6 in the uppermost smoke tube. To the flange 13 is connected the flanged pipe 14 (Fig. 4) to which the cold or relatively cold feed-water is admitted through the combination clack valve device 15 which is preferably the same or substantially the same in construction and working as that described and illustrated in the prior specification of 110 Letters Patent of the United States numbered 1,247,769 and dated the 27th day of November 1917.

21 is the usual steam pipe of the boiler leading from the steam dome into the saturated steam chambers of the superheater header.

As shown in Fig. 3 suitable supporting clips are provided for the longitudinal pipes of the superheater elements, these clips as 125 shown consisting of plates or strips 22, 22^a of steel or other suitable metal held against the outsides of the pipes of the short return loop portion of the element by rivets 23 which pass through a ring 24 between the 130
